(57) **CLAIM**

The ornamental design for a device for throwing objects, as shown and described.

DESCRIPTION

FIG. 1 is a bottom perspective view of my new design of a device for throwing objects;

FIG. 2 is a view of the left side of my new design of a device for throwing objects;

FIG. 3 is a view of the right side of my new design of a device for throwing objects;

FIG. 4 is a bottom view of my new design of a device for throwing objects;

FIG. 5 is a top view of my new design of a device for throwing objects;

FIG. 6 is a rear view of my new design of a device for throwing objects;

FIG. 7 is a front view of my new design of a device for throwing objects; and,

FIG. 8 is an enlarged fragmented perspective view of my new design of a device for throwing objects.

The broken lines are for illustrative purposes only and form no part of the design.
